UNITED STATES PATENT OFFICE.

HARRY M. PFLAGER, OF ST. LOUIS, MISSOURI, ASSIGNOR TO COMMONWEALTH STEE COMPANY, OF ST. LOUIS, MISSOURI, A CORPORATION OF NEW JERSEY.

CAR CONSTRUCTION.

1,280,081.

Specification of Letters Patent. Patented Sept. 24, 1918.

Application filed January 12, 1918. Serial No. 211,590.

To all whom it may concern:

Be it known that I, HARRY M. PFLAGER, a citizen of the United States, residing at city of St. Louis, State of Missouri, have invented a certain new and useful Improvement in Car Construction, of which the following is a full, clear, and exact description, such as will enable others skilled in the art to which it appertains to make and use the same, reference being had to the accompanying drawings, forming part of this specification, in which—

Figure 1 is a conventional illustration in side elevation showing my improved car construction.

Fig. 2 is a top plan view of the same.

Fig. 3 is a top plan view of one of the trucks used in my improved construction.

Fig. 4 is a side elevational view partly in section of one of my improved frames.

Fig. 5 is a horizontal sectional view on line 5—5 of Fig. 4.

Fig. 6 is a vertical sectional view on line 6—6 of Fig. 4.

This invention relates to a new and useful improvement in car construction of the type illustrated in Reissue Letters Patent No. 14,221, dated November 28, 1916, the original of which, Patent No. 1,147,430, was granted July 20, 1915.

In the construction shown in said original and reissue Letters Patent granted to me upon the dates beforementioned, the weight of the car body including the load, when loaded, is supported at the four corners of the car.

My present invention has for its object, to provide means for distributing the load of the car on the journals when unusual track conditions exist.

I prefer to provide this means in the form of a spring or springs, auxiliary to the main carrying springs, the auxiliary springs being capable of greater deflection and greater recoil travel than the main springs, so as not to affect the height of the drawbar from the track.

My present invention has as its principal object means to overcome this difficulty, this means consisting in the employment of a compensating spring or springs whose en-

ergies are stored up under normal conditions in readiness to be exerted in a direction to force the otherwise floating wheels down into the depression of the track whereby the treads and flanges of said wheels are not only caused to occupy their proper relation to the track, but part of the load of the car body at that corner where the floating wheels are located, is partially supported by said compensating springs. In the event that my present improvement is used under new steel cars, which, as stated before, are rigid in that they have very small deflection, the compensating springs will assist the rigid car body in supporting the load at that corner of the car wherein they are located, under the abnormal conditions above referred to. Where the car body is sufficiently flexible for its corners to sag or deflect and follow the otherwise floating wheels when they pass over or rest in a depression, these compensating springs may not be brought into action.

In the form of my invention illustrated in the accompanying drawings, the compensating springs are weaker than the load supporting springs, so that when the latter, which may be designated as the "major" springs, are under normal compression, the compensating spring or springs, which may be referred to as the "minor" spring or springs, are under compression, *i. e.* bottled up, the spring follower of the major springs being seated home against some solid part of the structure, this home seating of said follower being maintained in normal operations. However, if the minor springs are released from compression and have a tendency to float free, the minor spring will have its energies released so as to take up in part the freedom of the major springs, and compress them to the extent that the minor spring assists in supporting the load. By the expression "bottled up" is meant that the auxiliary or compensating springs 14, which are located in a pocket in the side truck frame and under a spring follower 8, will be held under compression at all times, under normal load conditions, the entire weight of the car being carried by the main supporting springs 12 which bear upon the

spring follower 8. When the wheels of the truck enter a depression and the truck side frames drop with the wheels, or one of them, the springs 12 will become exhausted, 5 or nearly so, and consequently the weight will be relieved from the follower plate 8 so that the energies of the springs 14 may be brought into play and to the extent that springs 14, whose energies are thus released, 10 lift the follower plate 8, they will slightly compress the springs 12 and to this extent assist in supporting the load. It is not intended, however, that the springs 14 shall, at any time, under normal conditions, assist 15 in supporting the load, because the spring follower 8 is normally in solid contact with the truck side frame and has no movement relative to the truck side frame, except under the abnormal condition above referred 20 to, wherein the spring follower 8 may be lifted away from the truck side frame or conversely the truck side frame may be depressed away from the spring follower 8 when spring follower 14 forces the wheels 25 to follow a depression in the track.

In the drawings, I have heretofore referred to Figs. 1 and 2 as conventionally illustrating a car body in which 1 is the body of the car, 2 the wheels, and 3 the track 30 having a depression 3^a over which the wheels at the righthand side of Fig. 1 are illustrated in full lines as floating over the depression, and in dotted lines as resting upon the track in the depression.

35 In Fig. 2, 4 indicates the pivotal point of the truck side frames, these being the points of reaction and showing that the car body is practically supported at its four corners.

Referring now to the details of construction of my present form of truck, 5 indicates 40 the truck side frame, preferably in the form of a steel casting, in which the journal boxes 6 are arranged for the reception of the axles 7 on which the wheels 2 are mounted. This 45 truck side frame is provided with a plurality of upwardly opening recesses in its central portion over which is arranged a spring follower 8 having depending lugs or guiding pins 8^a operating in the recesses 5^a of the 50 truck side frames. In this manner, the spring follower 8 is guided in its vertical movement.

9 indicates a spring follower having a bearing 9^a which co-operates with a bearing 55 10 secured to the underframe 11 of the car, this bearing co-operating with the concave bearing in the spring follower 9 so as to permit a rocking movement therebetween. The bearing plates 8 and 9 have telescopic 60 connection with each other and co-operate with supporting springs 12 interposed therebetween, there being a king pin 13 forming a pivotal connection between the bearing 9

and the underframing of the car. In the centrally arranged housing 5^b, there are located compensating springs 14 bearing on the underside of the follower plate 8. 15 indicates bolts carrying compression springs 16 which tend to hold the spring follower 8 upon its side truck frame and at the same 70 time limit the separating movement of these parts. The side truck frames of a pair are connected together by means of a tie bar 17 preferably pivotally located to the central portions thereof as shown. 75

In operation, the springs 12 constitute the supporting springs on the car and normally hold the compensating springs 14 under compression. In the event that the wheels pass over or rest in a depression in the track 80 and the springs 12 become exhausted, or nearly so, then the energies stored up in the springs 14 will be exerted on the under side of the follower plate 8 and assist in supporting the load. In doing this, they overcome 85 the action of the springs 16 whose principal function is to assist in restoring the spring follower 8 to its seat on the truck and to limit the separating movement of the parts,—as for instance, when the truck is not located under a car, as when being first assembled, or removed from a car for purposes of repair.

It is obvious that minor changes in the size, form and details of the various parts of my improved car construction may be made and substituted for those herein shown and described without departing from the spirit of my invention, the scope of which is set forth in the appended claims. 100

What I claim is:

1. In car construction, a car underframe, a truck side frame having pivotal connection therewith, a spring follower mounted thereon and normally arranged for solid engagement therewith, but capable of an upward vertical movement relative thereto, and a compensating device in the form of springs arranged beneath and co-operating with said spring follower. 105

2. In car construction, a car underframe, in combination with a truck side frame having pivotal connection therewith, supporting journals, supporting springs interposed between said car truck side frames and said underframe and normally seated solidly against said side truck frames, and a compensating yielding device located upon the car truck side frames whose energies are stored up, under normal conditions, and released under abnormal conditions, for the purpose described.

3. In car construction, a truck side frame, in combination with a spring follower having vertical movement relative thereto and a compensating device co-operating with said

spring follower, said spring follower being normally seated solidly against said truck side frame under normal conditions.

4. In car construction, a truck side frame, 5 in combination with a spring follower having vertical movement relative thereto, a compensating device coöperating with said

spring follower, and means for limiting the separating movement of said spring follower when actuated by said compensating device. 10

In testimony whereof I hereunto affix my signature this 3rd day of January, 1918.

HARRY M. PFLAGER.
